UNITED STATES PATENT OFFICE.

DOZIER FINLEY, OF BERKELEY, CALIFORNIA, ASSIGNOR TO THE PARAFFINE COMPANIES, INC., OF SAN FRANCISCO, CALIFORNIA, A CORPORATION OF DELAWARE.

PIPE-WRAPPING MACHINE.

Application filed March 23, 1925. Serial No. 17,483.

My invention relates to machines for wrapping pipe with a protective covering and one of the objects of the invention is the provision of a pipe wrapping machine of relatively simple construction having a minimum of specially machined parts so that the machine may be built at small expense.

Another object of the invention is the provision of a pipe wrapping machine which 10 may be moved from place to place as the need for it requires.

Another object of the invention is to provide a pipe wrapping machine in which the mechanism for turning the pipe and advancing it thru the machine is free of the complicated parts which characterize all 15 other pipe wrapping machines now known to me.

Another object of the invention is the provision of a pipe wrapping machine with 20 which a plurality of overlapping covering strips is placed on the pipe, one or more of the strips having applied thereto a cementing material for holding the strips in place, 25 such cementing material also being preferably waterproof and decay-proof.

My invention possesses other objects and features of advantage, some of which with the foregoing will be set forth in the following 30 description of the preferred form of my invention which is illustrated in the drawings accompanying and forming part of the specification. It is to be understood that I do not limit myself to the showing made by 35 said drawings and description, as I may adopt variations of the preferred form within the scope of my invention as set forth in the claims.

Referring to the drawings—

40 Figure 1 is a plan view of the pipe wrapping machine of my invention, showing a pipe being wrapped therein.

Figure 2 is a plan view of a buggy for supporting the end of the pipe as it emerges 45 from the machine.

Figure 3 is a vertical sectional view thru one end of the machine, the plane of section being indicated by the broken line 3—3 of Fig. 1.

50 Figure 4 is an elevation of a pipe supporting bracket on the machine, the direction of the view being indicated by the arrow 4 in Fig. 1.

Figure 5 is an elevation of the pipe sup- 55 porting and guide rolls, the direction of the

view being indicated by the arrow 5 in Fig. 1.

Figure 6 is a perspective view of a modified portion of my machine, and showing a method of applying the cementing mate- 60 rial.

In terms of broad inclusion the pipe wrapping machine of my invention comprises a main frame on which is arranged means for supporting a piece of pipe to be wrapped 65 and permitting it to turn about and move longitudinally of its axis. The frame is provided with ground contacting wheels so that it may be readily moved about. Movable arranged on the main frame is a secondary 70 frame, upon which are mounted pulleys, on which is an endless belt, one reach of which is adapted to encircle the pipe. A prime mover of any suitable type is also arranged on the movable frame to drive the belt. 75 Means are provided for locking the secondary frame in adjusted position so that the belt is in the desired angular relation to the pipe, movement of the belt then rotating the pipe and advancing it, the rate of advance 80 being determined by the angular relation of the belt to the pipe. If the belt is at right angles to the pipe axial rotation only, of the pipe, will occur upon movement of the belt. Upon adjustment of the secondary frame to 85 position the belt at an angle other than 90° to the axis of the pipe, movement of the belt results in a forward movement of the pipe at a rate determined by such angle.

Also arranged on the main frame are 90 means for supporting rolls of strip material which are drawn onto the pipe in a spiral as the pipe is rotated and advanced. This mounting means is also movable on the main frame so that the angular relation of the 95 wrapping strip to the pipe machine may be varied to correspond to the angular relation of the driving belt. Means are also provided for applying to the wrapping strip as it is drawn upon the pipe a cementitious material 100 for holding the strip in place and preferably this material is of a bituminous nature so that a high degree of resistance is provided to water and decay or fungoid growths. These latter qualities are of major import- 105 ance when the covered pipe is to be used underground or in positions in which it is subject to attack by corrosive fumes.

More particularly my device comprises a main frame 2, supported from the ground 110

by wheels 3, thus constituting a vehicle of conventional form which may readily be moved about. Arranged at the rear of the vehicle frame 2 are a pair of upwardly extending guide rolls 6, each mounted on a shaft 7, supported on the frame by a pivot pin 8, and angularly adjustable by means of the slotted arcuate end 9, in conjunction with the clamping nut 10. These guide rolls prevent lateral movement of the pipe 11 in the machine. The weight of the pipe is carried by a roll 12, journaled in suitable bearings 13, and extending under the pipe at an angle as shown in Figure 1. The angular position of these guide and support rolls relative to the axis of the pipe permits both rotary and axial movement of the pipe. Toward the forward end of the main frame is a bracket frame 14, in which is carried a pair of fixed shoes 16, each mounted on the bracket by means of a stud 17 and suitable lock nuts 18. One of these shoes is below the pipe and the other shoe is on the side of the pipe. On the opposite side of the pipe and above the pipe are shoes 19, mounted on studs 21, and resiliently pressed against the pipe by springs 22. The shoes are prevented from rotary movement by an arm 23, carrying a pin 24, which moves within an aperture in the bracket. The resilient shoes are provided to compensate for inequalities and projections which may occur on the pipe as it passes thru the supporting bracket.

Preferably pivotally mounted on the cross piece 26 of the main frame 2, is a secondary frame 27. Suitable locking means such as the threaded pin 28, passing thru the cross piece 29 of the secondary frame and engaging in the plate 26, is provided for fixing the position of the secondary frame on the main frame. Journaled in suitable bearings 30 on the secondary frame are two shafts 31 and 32 each carrying a pulley 33 over which a belt 34 is stretched. One reach of the belt is given a turn about the pipe as shown in Fig. 1 so that movement of the belt will rotate the pipe and at the same time move it longitudinally of its axis at a rate corresponding to the angular relation of the belt to the axis. The bearings 30 on which the pulleys are mounted are adjustable to permit the belt to be passed about pipes of different size. Connecting to the shaft 32 by a suitable reduction gearing 36 and clutch 37 is a prime mover 38 of any suitable type.

Mounted at the forward end of the vehicle frame is a tank 41 adapted to hold a cementitious material preferably of a bituminous nature which may be kept in a fluid condition by heat from the flues 43 of which there are conveniently two. Each of these flues is of U-form with ends opening on the side wall of the tank. A burner 44 con-

trolled by the valve 46, and fed thru the flexible conduit 47, provides means for heating the flues.

Arranged on one side of the pipe is a frame 48 pivotally mounted on a vertical axis, and provided with a suitable locking pin 49 so that it may be swung into the desired angular relation with the pipe and secured in that position. Arranged on this frame are a plurality of arbors 51, each carrying a roll 52 of strip material 53. Guide rolls 54 above the level of the tank, and guide rolls 56 within the tank, provide means for directing the covering strips into the material in the tank and upwardly to the pipe. The rolls 52 are offset with relation to each other as shown in Fig. 1 so that the covering strips are applied to the pipe in an overlapping relation, and since the strips are saturated with the bituminous material in the tank they are securely cemented to each other and to the pipe.

Arranged on the opposite side of the pipe is another frame 61 also mounted for movement about a vertical axis and provided with similar locking means 62 for fixing its position. This frame also carries an arbor 63, on which a roll 64 of strip covering material 66 is carried. This strip of covering material does not pass thru any cementitious material but is wound over the other two strips adhering to them and presenting a dry exterior surface.

A piece of pipe is placed within the machine and the wrapping strips started by proper manipulation with the hands. A second piece of pipe 67 is then supported in alignment with the pipe in the machine, on any suitable means and connected to the pipe in the machine by means of an expanding plug 68 comprising two halves which may be forcibly separated by the screw 69. With the frames carrying the driving belt and the covering strips properly adjusted to the desired angular relation with the pipe, the prime mover 38 is started to feed the pipe thru the machine, successive lengths of pipe being connected by expanding plugs, as the wrapping progresses. The emerging pipe is carried on any suitable supports such as the buggy 71, having ground-contacting wheels 72, and a handle 73. The buggy is provided with a head 74, on which rollers 76 are journaled in such manner as to engage the interior surface of the pipe at its advancing end. The buggy is in charge of a workman whose duty it is to guide it as the advancing pipe moves it forwardly. As each length of wrapped pipe emerges, the wrapping is cut at the joint and the plug removed.

In Fig. 6 I have shown an alternative form of apparatus for applying the cementitious material to the covering strip. This structure is useful where only a single strip is to be wound upon the pipe, and it is sufficient

to apply the cementitious material upon the inner surface of the strip as it reaches the pipe. A tank 81 is suitably supported on the frame and heated by means similar to those already described. The tank is provided with a conduit 82, the end of which is furnished with a valve 83, positioned over and discharging upon the strip 84 being wound upon the pipe. The strip is unwound from a roll 86, carried on a frame 87, mounted to turn on a vertical axis as already explained in connection with the frame 61.

I claim:

1. A pipe wrapping machine comprising means for supporting the pipe, a movable frame, pulleys on said frame, an endless belt on said pulleys and having one reach adapted to encircle the pipe, and means for driving the belt arranged on said movable frame.

2. A pipe wrapping machine comprising means for supporting the pipe, a movable frame, means on said frame and including an endless belt adapted to encircle the pipe for turning the pipe and simultaneously advancing it thru the machine, a second movable frame, and means on said second frame for holding a supply of pipe covering material.

3. A pipe wrapping machine comprising means for supporting the pipe, a movable frame, means on said frame and including an endless belt adapted to encircle the pipe for turning the pipe and simultaneously advancing it thru the machine, a second movable frame, means on said second frame for holding a supply of pipe covering material, and means for applying to said covering material a cementing material.

4. A pipe wrapping machine comprising a main frame, ground contacting wheels arranged on said frame, a driving unit frame pivoted on the main frame, means on said driving unit frame and including an endless belt adapted to encircle the pipe for turning

the pipe and simultaneously advancing it thru the machine, means arranged on the main frame for feeding a covering strip to said pipe, and means for applying a cementing material to said covering.

5. A pipe wrapping machine comprising a main frame, ground contacting wheels arranged on said frame, a driving unit frame pivoted on the main frame, means on said driving unit frame and including an endless belt adapted to encircle the pipe for turning the pipe and simultaneously advancing it thru the machine, a covering strip frame pivoted on said main frame, means on said covering strip frame for holding a roll of covering material, and means for applying a cementing material to said covering material.

6. A pipe wrapping machine comprising means for supporting the pipe, a movable frame, pulleys on said frame, an endless belt adapted to tractionally engage said pipe and arranged on said pulleys, and means for driving said belt.

7. A pipe wrapping machine comprising means for supporting the pipe, a movable frame, pulleys on said frame, an endless belt adapted to tractionally engage said pipe and arranged on said pulleys, means for driving said belt, a second movable frame, and means on said second frame for holding a supply of pipe covering material.

8. A pipe wrapping machine comprising means for supporting the pipe, a movable frame, pulleys on said frame, an endless belt adapted to tractionally engage said pipe and arranged on said pulleys, means for driving said belt, means for holding a supply of pipe covering material, and means for applying to said covering material a cementing material.

In testimony whereof, I have hereunto set my hand.

DOZIER FINLEY.
